M. SUBBER.
WINDOW AND DOOR LOCK.
APPLICATION FILED MAY 25, 1920.

1,389,709.

Patented Sept. 6, 1921.

UNITED STATES PATENT OFFICE.

MORRIS SUBBER, OF PHILADELPHIA, PENNSYLVANIA.

WINDOW AND DOOR LOCK.

1,389,709.

Specification of Letters Patent. Patented Sept. 6, 1921.

Application filed May 25, 1920. Serial No. 384,100.

To all whom it may concern:

Be it known that I, MORRIS SUBBER, a citizen of the United States, residing in the city and county of Philadelphia, State of Pennsylvania, have invented a new and useful Window and Door Lock, of which the following is a specification.

My invention consists of a device adapted to lock a window or door, the same being effective in operation, of simple and inexpensive construction and easily operative, as will be hereinafter set forth.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a perspective view of a window lock or fastening embodying my invention.

Fig. 2 represents a longitudinal section thereof on an enlarged scale.

Fig. 3 represents a side elevation of a detached portion thereof.

Fig. 4 represents an elevation of an escutcheon employed.

Fig. 5 represents a side elevation of certain members in separated condition and on an enlarged scale.

Fig. 6 represents a partial front elevation and a partial longitudinal section of a door lock or fastening embodying my invention.

Fig. 7 represents a top or plan view partly in section of the door lock or fastener embodying my invention, a portion of the door and door jamb being also in section, the scale of said Fig. 7 being slightly different from that of Fig. 6.

Similar numerals of reference indicate corresponding parts in the figures.

Referring to the drawings.

1 designates a barrel which is adapted to be located in the meeting rail 2, of the lower sash of a window, and 3 designates a socket which is adapted to be located in the meeting rail 4 of the upper sash of a window.

The barrel has on the exterior thereof

near its outer end the escutcheon 5 which is secured to the inner side of the meeting rail 2 by the screws 6 or other suitable means, thus retaining said escutcheon and consequently the barrel firmly in position.

The socket 3 is provided with the face plate 7 which is secured to the inner side of the meeting rail 4 by the screws 8 or other suitable means, thus retaining said plate and said socket firmly in position.

In the barrel is the movable or slidable bolt 6 or plunger 9 the inner end of which comprises its head portion 10 which is adapted to enter the socket 3 and thus lock the sashes in fully closed position, it being noticed that the meeting rail 4 is provided with an additional socket 11 which may receive the head portion of the bolt and so lock the sashes in partly open position.

Within the barrel encircling the bolt 9 is the coil spring 12 whose ends are adapted to bear respectively against the inner face of the escutcheon 5 and the shoulder 13 on the head portion 10 of the bolt, the socket having centrally therein the rubber or other cushion 14 with which the contiguous end of the portion 10 of the bolt may contact and which may be compressed, thus more firmly retaining the bolt in the socket and preventing rattling thereof as well as the meeting rails of the sashes.

Extended from the escutcheon and consequently from the face of the meeting rail is the tube 15 in whose wall is the longitudinally extending slot 16, it being noticed that the bolt 9 is extended outside of the barrel so that a portion 17 of the same fully occupies the tube 15 and is slidable therein. Connected with the said extension at a certain distance from its outer terminal is the pin 18 forming a finger piece for the operation of the bolt, as will be hereinafter referred to. In the wall of the slot 16 adjacent to the escutcheon 5 is the recess 19 which is adapted to receive the finger piece 18 on turning the bolt by the latter, thus retaining the bolt in the socket and consequently locking the sashes.

In order to prevent opening of the bolt by

access to the same and tampering therewith from between the meeting rails or from any improper return rotation of the bolt, I employ the bent catch 20 which is adapted to be connected removably with the escutcheon 5 so as to extend outwardly therefrom and engage with the side of the finger piece 18 to control the same when the latter occupies the recess 19 in the wall of the slot 16 of the tube 15, thus preventing said finger piece from removal from said recess and consequently preventing motion of the bolt from the socket 3 the compressed cushion 14 then causing the finger piece 8 to be pressed outwardly tightly against said catch 20.

The operation is as follows:—

The pin 20 having been removed and the bolt 9 occupying its outermost position, the finger piece 18 having moved with the bolt 20 through the slot 16 of the extension 15, and the sashes having been fully closed, the bolt is pushed in by the finger piece so that its head portion enters the socket which piece has been grasped for the purpose. When 25 said finger piece reaches the recess 19 the bolt is turned say to the right by said piece so that it enters said recess and said bolt has its head portion 10 occupy the socket, thus locking the sashes, the spring 12 having 30 been compressed as has been stated. Then to prevent improper return of the bolt, the pin 20 is connected with the escutcheon and so controls the finger piece 18 and consequently the bolt from movement, whereby 35 the sashes remain locked.

When the sashes are to be unlocked the controlling pin 20 of the finger piece 18 is removed, when the latter is grasped and the bolt rotated by the same, say to the left, the 40 finger piece then leaving the recess 19 when the bolt is drawn out by the finger piece when the spring 13 is compressed, the head of the bolt then leaving the socket and entering the barrel, and so the sashes are 45 unlocked. The finger piece may now be turned with the bolt and inserted in either of the recesses 21 in the outer terminal of the tube 15 on opposite sides of said tube under the compression of said spring 12 whereby the 50 tube is prevented from motion. The retaining catch 20 may be returned to the escutcheon when the device is in position for the next operation of locking the sashes. The pin 20 is adapted to overhang the finger 55 piece 18 so as to lock the latter and consequently the bolt, but in order to unlock the bolt said pin requires to be rotated so as to clear said finger piece when the latter is free to be moved outwardly in the slot 16 60 of the tube 15 to withdraw the bolt from the socket 3, but said pin 20 may be unscrewed from the escutcheon 5 and so entirely removed from the latter whereby it

no longer controls said piece 18 when said piece may be returned into the slot 16 and 65 moved out of the same carrying with it the bolt 9 for the same purpose as above.

The tube 15 comprises an outward extension of the barrel, and the bolt is sufficiently long to occupy both said barrel and tube. 70

In Figs. 6 and 7 I show the device applicable to a door to lock the same, the socket 3 being fitted in the door jamb, and the barrel fitted on the door frame adjacent to the jamb. A recess 22 is formed in the door at 75 the inner terminal of the barrel to permit the play of the bolt and the finger piece 18. In this case a face plate such as 23 is secured to the door in front of said recess 22 and has thereon the longitudinally extending slot 24 which is adapted to have the finger piece play therein, said slot having one end adapted to have the finger piece 18 abut against it when the head of the bolt occupies the socket 3, the other end of said 85 slot having an angular extension 26 in the terminal of which when the bolt is rotated said finger piece may abut and in which it may be held when the bolt is drawn back from the socket and the sashes are unlocked. 90

Having thus described my invention what I claim as new and desire to secure by Letters Patent, is:—

1. In a lock of the character stated, a 95 slideable and rotatable bolt, a barrel adapted to freely contain the same, a socket which an end of said bolt is adapted to occupy, a finger piece on said bolt adapted to operate the same to remove it from said socket, and said barrel having therein a longitudinally 100 extending slot in which said finger piece is movable, and a catch on a member to be locked adapted to have said finger piece engaged therewith.

2. In a lock of the character stated, a 105 slideable and rotatable bolt, a barrel in which said bolt is freely contained, a tubular member extending outwardly from said barrel in which a corresponding portion of said bolt is freely received, said member having a 110 longitudinally extending slot in the wall of which is a recess, a finger piece on said bolt, said piece being adapted to lockingly occupy said recess when said bolt is rotated, and a catch on a stationary part to be locked 115 adapted to engage said finger piece to control the same from motion.

3. In a lock of the character stated, a barrel, a tubular member continuous of said barrel, a slideable and rotatable bolt in said barrel and member, and a finger piece on the side of said bolt, a catch engageable with said finger piece adapted to lock the same and consequently the bolt, a face plate having a longitudinally extending slot in which 125 said piece is slideable, and recesses in the op-

posite ends of the wall of said slot adapted to receive said piece in the locked and unlocked positions of said bolt respectively.

4. In a lock of the character stated, a slide-
able and rotatable bolt, a barrel adapted to
freely contain the same, said barrel having
therein a longitudinally extending slot, an
operating finger piece on said bolt movable

in said slot, and a catch on a member to be
locked, said catch being adapted to over- 10
hang said finger piece and to be moved
therefrom.

MORRIS SUBBER.
